UNITED STATES PATENT OFFICE.

EUGENE KOEHLER, OF PHILADELPHIA, PENNSYLVANIA.

TELEPHONE.

No. 922,001.

Specification of Letters Patent.

Patented May 18, 1909.

Application filed January 12, 1909. Serial No. 471,851.

To all whom it may concern:

Be it known that I, EUGENE KOEHLER, a citizen of the United States, residing at Philadelphia, in the county of Philadelphia and 5 State of Pennsylvania, have invented certain new and useful Improvements in Telephones, of which the following is a specification.

My invention relates to improvements in telephones, the object being to provide an 10 improved telephone constructed to transmit speech when placed against the body of the sender, to utilize the vibrations of the body, as distinguished from the sound waves, such as utilized in the ordinary construction of 15 telephone.

A further object is to provide improvements of this character, constructed and adapted to be self-sustaining upon the body of the user, enabling him to employ his hands 20 for any use desired.

Heretofore in the construction of telephones, it has been the practice to construct the telephone with a transmitter into which the sender speaks, utilizing the sound waves 25 to vibrate the transmitter. I have discovered that the transmitter, when placed against the body, will transmit speech by reason of the vibrations of the body of the user, and my invention is designed as a telephone of this kind.

The invention consists in certain novel features of construction, and combinations, and arrangements of parts as will be more fully hereinafter described and pointed out 35 in the claims.

In the accompanying drawings, Figure 1 is a view in elevation, partly in section illustrating my improvements. Fig. 2, is an enlarged view in cross section, and Fig. 3, is a 40 view taken at right angles to Fig. 2, and partly in section.

The telephone proper comprises three members, 1, 2 and 3. The member 1 is a tubular member having an ordinary receiver 45 4 at its end, adapted to be positioned near the ear of the user, and this member 1 is provided with an eye 5 to enable the telephone to be hung up out of the way. The member 2 is also a tubular or hollow member, and has an 50 ordinary transmitter 6 at its free end. The member 3 is a spring bar, and all of said members, 1, 2 and 3 are provided, or made integral with circular disks 7, 8 and 9 respectively, located side by side, spaced apart by 55 washers 10, and pivotally secured upon a journal pin 11. This journal pin 11, also

secures to the opposite sides of the assembled disks 7, 8 and 9, cup-shaped casings 12. The journal pin 11 is provided with a head 13 at one end, and a headed screw 14 is screwed into the other end of the journal pin, to effectually clamp the casings 12 and disks 7, 8 and 9, in assembled formation, permitting pivotal movement of the members with relation to each other.

In the drawings, I have illustrated a simple construction of circuit closer, in which 15 represents contact points on the disk 9, movable with member 2, and contact points 16 on the disk 8, connected with member 1. 70 These contact points are connected by wires 17, with the transmitter 6 and the receiver 4, and are adapted when the contact points 15 engage the contact points 16 to close the electric circuit, and call up the central office, 75 as is ordinarily the case with telephones in use, and an alarm 19 is connected by wires 20 with the telephone in any approved manner, so as to sound the alarm when a party is being called by the central office.

The construction and operation of the circuit wires are not shown, but will be the same as in any ordinary telephone.

A spring 21, preferably of the ordinary clock spring type, is located in one of the 85 casings 12, secured at one end to the journal 11, and at its other end to the disk 9, and as the journal 11 is locked to the disk 7, by means of a key 22, it will be seen that the tension of the spring 21, tends to move the 90 members 2 and 3 toward each other, and hence move the contact points 15 away from the contact points 16.

When the device is to be used, the members 2 and 3 are drawn apart and placed over 95 the shoulder of the user, the body being clamped between the members and holds them in such position, that the contact points 15 and 16 will close the electric circuit and call central. To steady the device, a 100 lateral prop 23 is secured to the member 1, by means of a set screw 24, and prevents lateral tilting of the device when in use. When in position on the body, with the receiver 4 close to the ear, the user talks in the 105 ordinary tone of voice, and the speech will be transmitted by the transmitter 6, through the medium of the vibrations of the body.

When the device is not desired for use, and is removed from the shoulder of the user, 110 spring 21 will break the electric circuit as above explained, and the telephone may be

nung up by means of the eye 5, until again desired.

The transmitter is shown in contact with the breast of the user, but may be placed on almost any part of the body, and hence I do not restrict myself to the precise details set forth, but consider myself at liberty to make such changes and alterations as fairly fall within the spirit and scope of my invention.

10 Having thus described my invention what I claim as new and desire to secure by Letters Patent is:

1. In an apparatus of the character described, the combination with a transmitter and an arm, said arm and transmitter constituting a body clamp to clamp the body between them, and a receiver supported by said transmitter and arm.

2. In an apparatus of the character described, the combination with a transmitter, and a spring arm having elastic connection with the transmitter, whereby a body may be clamped between said transmitter and said arm, and a receiver connected with said transmitter and spring arm at their juncture.

25 3. In a telephone, the combination with a receiver, a transmitter, and a spring arm, of

disks on all of said members located side by side, a journal pivotally connecting said disks, a spring normally pressing said transmitter and spring arm toward each other, and electric contacts between the transmitter and the receiver normally held apart by means of the spring.

4. In a telephone, the combination with a receiver, a transmitter, and a spring arm, of disks on all of said members located side by side, a journal pivotally connecting said disks, a spring normally pressing said transmitter and spring arm toward each other, electric contacts between the transmitter and the receiver normally held apart by means of the spring, said transmitter and arm adapted to clamp a body between them, and a prop secured to the receiver and adapted to rest on the shoulder of the body.

In testimony whereof I have signed my name to this specification in the presence of two subscribing witnesses:

EUGENE KOEHLER.
